**METHOD OF MAKING 2,2'-BIPHENYLDICARBOXY-
ALDEHYDE**

Murray G. Sturrock and Edwin L. Cline, Pittsburgh, and Kenneth R. Robinson, Monroe Heights, Pa., assignors to Koppers Company, Inc., a corporation of Delaware

No Drawing. Filed June 26, 1958, Ser. No. 744,638

3 Claims. (Cl. 260—599)

This invention relates to a method of making an aromatic dialdehyde derivative from phenanthrene. In one specific aspect, it relates to an ozonation-hydrolysis technique for making diphenaldehyde, 2,2'-biphenyldicarboxy-aldehyde.

Phenanthrene, which comprises 3-5% of tar recovered from high temperature carbonization of bituminous coal, is a compound of limited chemical activity for which no large scale uses are known. Because of the relative abundance of phenanthrene in coal tar and in other source materials, workers in the art have long been in quest of a simple and efficient method for converting phenanthrene into one of its more useful derivatives, e.g. diphenaldehyde.

As early as 1905, one Harries (Annalen 343,373) attempted to prepare derivatives of phenanthrene by the ozonation of the parent compound in chloroform solution. He obtained as a product the explosive phenanthrene diazonide, but he prepared no further derivatives of that compound.

In recent years, there has been renewed interest in the ozonation of phenanthrene. Schmitt et al., JACS, 77, 5640 (1955), ozonized phenanthrene in acetic acid and in chloroform. They isolated what they believed to be the mono-ozonide in 85% yield and converted it to diphenaldehyde by pouring the acetic acid solution of the ozonide into four volumes of cold water and allowing the ozonide to hydrolyze at room temperatures over a two-day period. A 43.5% yield of diphenaldehyde, based on the amount of phenanthrene charged, was obtained. The relatively small yields, the likelihood of the formation of explosive ozonides, and the difficulty encountered in the recovery of solvent are serious handicaps to commercial development of such a process.

Bailey, JACS, 78, 3811 (1956), ozonized phenanthrene in anhydrous methyl alcohol solution at temperatures between 0 and -60° C., thereby obtaining a 78% yield of a product. By hydrolyzing this product in 10% aqueous caustic soda solution, Bailey obtained a 65% over-all yield, based upon the phenanthrene charged, of diphenaldehyde acid (2'-formyl-2-biphenylcarboxylic acid, M.P. 134° C.). He obtained a 65% over-all yield of diphenic acid by hydrolyzing the ozonation product in the presence of hydrogen peroxide and caustic. In the course of his work, Bailey also made diphenaldehyde in an 84% over-all yield by ozonation of phenanthrene in anhydrous methyl alcohol solution, treatment of the ozonation product thus formed with sodium iodide in acetic acid solution, removal of the liberated iodine with sodium thiosulfate and precipitation of the product by manifold dilution with water. While Bailey's work resulted in improvement over that of Schmitt et al., the cost of making the diphenaldehyde by his method is still too high to be regarded as economically attractive. To make the diphenaldehyde, he was forced to resort to using sodium iodide, an expensive chemical reducing agent, in order to obtain his desired product.

2

We have discovered a novel method for converting phenanthrene in high yield to diphenaldehyde by a combined ozonation-hydrolysis technique.

It is, therefore, an object of the present invention to provide a method for making diphenaldehyde in high yield at greatly reduced cost.

In accordance with the invention, phenanthrene is suspended in a medium comprising methyl alcohol and contacted with a gas stream containing ozone to make an ozonation product. This ozonation product is then hydrolyzed in the presence of water at a pH below 7.5 to form the diphenaldehyde. Hydrolysis and removal of methyl alcohol from the system may be accomplished concomitantly. Diphenaldehyde is recovered from the hydrolyzed mixture, generally by solvent extraction, after removal of the alcohol.

This application is a continuation-in-part of our copending application S.N. 732,081, filed April 30, 1958. In that copending application we disclosed and claimed a method of making ortho-ortho' di-substituted biphenyl derivatives from phenanthrene comprising suspending phenanthrene in a mixture of water and a lower aliphatic alcohol having from 2-4 carbon atoms, contacting the suspension with a gas stream containing ozone to make an ozonation product, and hydrolyzing the ozonation product to form one or more of a series of ortho-ortho' di-substituted biphenyl derivatives. The particular biphenyl derivative obtained depends primarily upon the pH of the reaction mixture during the hydrolysis step. The present invention differs from that of our copending application in that herein ozonation is conducted in a medium consisting essentially of anhydrous methyl alcohol or methyl alcohol containing up to 35% by weight water. Thus, for purposes of this invention, an anhydrous alcohol, rather than an alcohol-water medium, can be used; and if water is present during ozonation, in contrast with the invention of our copending application, only a limited amount of water, viz: up to 35% by weight of the suspension medium, can be used during the ozonation step. This invention also differs from that of our copending application in respect of the operable range of pH during the hydrolysis step.

As we have already indicated, the suspension medium of the present invention consists essentially of absolute methyl alcohol or methyl alcohol in admixture with up to 35% water, based upon the total weight of the suspension medium. If more than 35% water is present, the phenanthrene particles cannot be easily wetted and suspended. If adequate wetting is not attained, the particles tend to float upon the surface of the medium and good contact with ozone cannot be achieved. Obviously, this results in a greatly diminished yield of product.

Among the lower aliphatic alcohols, methyl alcohol, since it does not form an azeotrope with water, is unique. If ozonation is conducted in anhydrous methyl alcohol, water is added thereafter to effect hydrolysis. Methyl alcohol boils well below the boiling point of water and, because of this property, it can be readily separated from the hydrolyzed mixture by distillation and reused in its anhydrous form. Since the other lower aliphatic alcohols, e.g. tertiary butyl alcohol, form azeotropes with water, their use is restricted to ozonation systems employing an alcohol-water medium because of the difficulties entailed in recovering the absolute alcohol from water by the requisite addition of a third component.

The concentration of the phenanthrene in the suspension may vary widely. The important consideration is to provide a well-agitated suspension and thereby promote intimate contact between the ozone and the phenanthrene in solution as well as between the solvent and phenanthrene crystals, so that resaturation of the solvent with phenanthrene is attained rapidly. Generally, the sus-

suspension contains between about 5 and 30% by weight phenanthrene.

An oxygen-containing gas is used as a carrier for the ozone during the reaction. The type of gaseous carrier and the concentration of ozone therein depends upon the type of equipment used. Certain generators provide a stream of ozone in air in concentrations ranging from 0.5-8% by weight. Others provide ozone in oxygen, the concentration of ozone being between 2 and 16% by weight. The entire gamut of ozone concentrations provided by either type of generating equipment is suitable for purposes of the present invention.

It is of utmost importance to provide intimate contact between the ozone and the phenanthrene. Conventional equipment may be used to disperse the ozone in the phenanthrene suspension. It is preferable to introduce the ozone-containing gas in the form of small bubbles to insure intimacy of contact. The rate of ozone addition is determined by the ability of the phenanthrene to absorb the ozone. It is, of course, commercially desirable to ozonize as rapidly as possible. Care should be taken to avoid a rate of ozone addition greater than the rate of absorption of the ozone by the reaction mixture. Usage of ozone in this manner is obviously wasteful. Moreover, explosive mixtures of gases may be formed in the equipment. The rate of ozone addition may be conveniently governed by an ozone meter placed downstream from the reaction mixture to determine whether all of the ozone added is being absorbed.

To obtain high yields of diphenaldehyde by the methods of the present invention, it is desirable to use at least a stoichiometric quantity of ozone based upon the starting amount of phenanthrene (a 1:1 mol ratio).

The reaction between ozone and the phenanthrene is almost instantaneous. The reaction time will, therefore, depend upon the starting quantity of phenanthrene and the intimacy of the contact between ozone and the phenanthrene. The reaction is continued until the desired quantity of ozone has been absorbed.

The reaction is conducted at atmosphere pressure (although higher or lower pressures can be used) over a temperature range of, for example, -20 to 40° C. The lower limit is established by the freezing point of the particular medium used. Operation at temperatures below those conveniently obtained with cooling water is possible, but generally the increased ozone solubility obtainable by this means cannot justify the high equipment costs involved. The upper limit is the boiling point of the solvent at the pressure used. It is less expensive, and therefore preferable, to conduct the reaction at ambient temperatures.

An important feature of the present invention is the particular set of conditions used during the hydrolysis step. If absolute methyl alcohol is used as a solvent, it is necessary to add water to the reaction mixture after the ozonation has been completed. The amount of water added must be at least sufficient to effect hydrolysis, i.e. 1 mol of water for each mol of ozonation product. There is no particular upper limit on the amount of water to be added, although it is obviously inconvenient during processing to handle excessive volumes of water. Conveniently, an amount of water equal to the weight of the suspension medium is added. If the suspension medium for ozonation contains an amount of water sufficient for hydrolysis, obviously no water need be added.

In the present invention, pH control of the reaction mixture during hydrolysis is of paramount importance. If the pH of the mixture is maintained below about 7.5, diphenaldehyde is obtained as a product in yields of 90% and higher. This result is quite astonishing in view of the teachings of the art. For example, Bailey, *supra*, resorted to treatment of his ozonation product with the expensive reagent, sodium iodide, in acetic acid solution to obtain an 84% yield of diphenaldehyde. The pH of the reaction mixture during the hydrolysis step is easily maintained at below about 7.5 by avoiding the addition of any substan-

tial amount of an alkaline-reacting substance. Ordinarily, the pH of the methyl alcohol reaction medium after ozonation ranges between about 2 and 4. If the addition of water is required to effect hydrolysis, the pH will rise slightly, but in any case, it will be substantially neutral or slightly on the acid side.

Hydrolysis and removal of the methyl alcohol are conveniently accomplished concomitantly. Thus, to hydrolyze the ozonation products of the present invention, the reaction mixture is heated to its boiling point, under reflux conditions if desired, preferably at atmospheric pressure. Since it is unnecessary to hydrolyze under total reflux, methyl alcohol is conveniently distilled over almost immediately after the reaction mixture is brought to the required temperature for hydrolysis. Hydrolysis and distillation can be accomplished under vacuum, but it is obviously preferable to work at atmospheric pressure because of equipment costs involved. Hydrolysis and distillation can be accomplished in separate steps by first hydrolyzing the ozonation product at a temperature somewhat below the boiling point (or under total reflux) and thereafter distilling off the suspension medium. No particular advantage is seen in such a technique. After the methyl alcohol is removed, the diphenaldehyde is recovered from the remaining aqueous solution by decantation or by extraction with common organic solvents such as benzene, carbon tetrachloride, toluene, and the like. Evaporation of the solvent extract yields diphenaldehyde as a yellow solid.

Any phenanthrene impurity can be removed from the product by distillation, recrystallization, or conversion of the diphenaldehyde to its sodium bisulfite adduct with subsequent separation by extraction or filtration.

The aqueous solution from which the diphenaldehyde has been recovered contains up to about 75% of theory of hydrogen peroxide. Thus, our process not only provides good yields of the desired diphenaldehyde, but, in addition, high yields of a valuable by-product, hydrogen peroxide, are obtained.

Unlike other aromatic aldehydes, diphenaldehyde is extremely stable to oxidation. It is not oxidized by air or by hydrogen peroxide; and peracetic acid attacks it only very slowly. Treating diphenaldehyde with boiling nitric acid, or chlorine, converts it to 9,10-phenanthraquinone in about 50% yield. When diphenaldehyde is heated at pH above 10, it undergoes an intra-molecular Cannizzaro reaction to form the alcohol-acid, 2'-hydroxymethyl-2-biphenylcarboxylic acid. This latter compound is converted almost quantitatively to diphenic acid in the presence of boiling concentrated nitric acid. Diphenaldehyde is readily reduced as, for example, by lithium aluminum hydride to form the corresponding dialcohol, 2,2'-biphenyl-dimethanol. The dialdehyde is readily condensed with phenols to give a light-fast dyestuff analogous to the dyes of the triphenylmethane series. When heated with urea, diphenaldehyde forms insoluble, infusible condensation products useful as ion exchange resins. Diphenaldehyde is particularly adaptable for uses wherein stability against oxidation is desirable, e.g. in perfume manufacture and in the making of light screening agents.

Our invention is further illustrated by the following examples.

Example I

Five parts (0.028 mol) of phenanthrene were slurried with 100 parts of methyl alcohol. An oxygen stream containing 4.12% ozone was introduced at a rate of 0.405 part per minute. The temperature of the reaction mixture was maintained in the range of 0 to -20° C. during the absorption of the ozone. A total of 0.0322 mol of ozone was introduced, of which only a negligible amount was recovered in the potassium iodide trap.

One hundred ml. of ice water were added and the ozonation product was hydrolyzed by heating the mixture to its boiling point. The alcohol was recovered concomitantly by distillation. As the alcohol was removed,

a yellow oil, which solidified partially upon cooling, began to separate from the aqueous solution. This oil was completely separated from the solution by repeated extraction with benzene.

Evaporation of the benzene extract yielded 5.8 parts of yellow oily solid material identified as diphenaldehyde by infrared analysis. The yield obtained represented 92% of theory, based upon the weight of phenanthrene charged.

The remaining aqueous solution was found to contain active oxygen. The solution was treated with dilute sulfuric acid and potassium iodide and the iodine thus liberated was then titrated with sodium thiosulphate. The results of the titration showed that the aqueous solution contained hydrogen peroxide in an amount equal to 73% of theory.

Example II

Five parts (0.028 mol) of phenanthrene were dissolved in 100 parts of hot methyl alcohol and the solution was thereafter rapidly cooled to -20° C . with vigorous stirring. This mixture was then ozonized with an oxygen stream containing 3.91% ozone. The ozone-oxygen mixture was introduced at the rate of 0.405 part per minute. The reaction mixture was kept at a temperature of 0° C . to -20° C . during the ozonation. A total of 0.0322 mol of ozone was introduced, of which only a negligible amount was recovered in the potassium iodide trap.

One hundred ml. of ice water was added to the reaction mixture (pH about 3.5) and the ozonation product was hydrolyzed by heating the mixture to its boiling point. The alcohol was removed concomitantly by distillation. As the alcohol was removed, a yellow oil separated and solidified partially on cooling. The organic material was removed from the aqueous solution by benzene extraction. Evaporation of the benzene extract yielded 5.9 parts of a yellow oily solid, which contained no active oxygen. The oily solid (5.4 parts) was extracted with sodium bisulfite solution and yielded 0.3 part of insoluble material consisting essentially of phenanthrene (representing a 93.5% ozone attack on the phenanthrene charged). The sodium bisulfite soluble material amounted to 5.0 parts (98.2% yield based on the phenanthrene reacted or 92.4% based on the phenanthrene charged) and was shown to be essentially diphenaldehyde by infrared analysis.

Example III

Five parts (0.028 mol) of phenanthrene were dissolved in 88 parts of methyl alcohol by warming, and this solution was added to 12 parts of ice water with vigorous stirring. This mixture was then ozonized at room temperature with an oxygen stream containing 7.89% ozone. The ozone-oxygen mixture was introduced at the rate of 0.81 part per minute. A total of 0.0323 mol of ozone was introduced, of which 0.0001 mol passed through the reaction mixture and was recovered in the potassium dioxide trap.

After ozonation, the reaction mixture (at a pH of 1.5) was diluted with 38 parts of water. The mixture was heated to its boiling point to effect hydrolysis of the ozonation product and the methyl alcohol removed simultaneously by distillation. The organic material was recovered by extraction with benzene. Evaporation of the benzene yielded 5.9 parts of a yellow oil, which contained no active oxygen. The oil (5.8 parts) was extracted with sodium bisulfite solution and yielded 0.1 part of insoluble material consisting essentially of phenanthrene (representing 98% attack on the phenanthrene charged). The sodium bisulfite soluble material amounted to 5.5 parts (96.8% yield based on phenanthrene reacted or 96.4% based on the phenanthrene charged), and was shown to be essentially diphenaldehyde by infrared analysis.

Example IV

Five parts (0.028 mol) of phenanthrene were dissolved in 70 parts of hot methyl alcohol and this solution was added to 30 parts of ice cold water with vigorous stirring. This slurry was then ozonized at room temperature with an oxygen stream containing 7.62% ozone. The ozone-oxygen mixture was introduced at the rate of 0.81 part per minute. A total of 0.0333 mol of ozone was introduced, of which 0.0011 mol passed through the reaction mixture and was recovered in the potassium iodide trap.

After ozonation, the reaction mixture (at a pH of 2.0) was diluted with 20 parts of water and heated to its boiling point to effect hydrolysis. The methyl alcohol was removed simultaneously by distillation. The organic material was removed by extraction with benzene. Evaporation of the benzene yielded 5.9 parts of a yellow orange oil, which contained no active oxygen. The oil (5.7 parts) was extracted with sodium bisulfite solution and yielded 0.5 part of insoluble material consisting essentially of phenanthrene (an ozone attack of 90% based on the phenanthrene charged). The sodium bisulfite soluble material amounted to 4.9 parts (95.7% yield based on the phenanthrene reacted or 86% based on the phenanthrene charged), and was shown to be essentially diphenaldehyde by infrared analysis.

Example V

30 Five parts (0.028 mol) of phenanthrene were dissolved in 50 parts of hot methyl alcohol and this solution was added to 50 parts of ice cold water with vigorous stirring. This slurry was then ozonized at room temperature with an oxygen stream containing 7.9% ozone.

35 The ozone-oxygen mixture was introduced at the rate of 0.81 part per minute. A total of 0.0443 mol of ozone was introduced, of which 0.0121 mol passed through the reaction mixture and was removed in the potassium iodide trap.

40 After ozonation, the reaction mixture (having a pH of 2.0) was hydrolyzed by heating and simultaneously distilled to remove the methyl alcohol. The organic material was removed by extraction with benzene. Evaporation of the benzene yielded 5.3 parts of a yellow

45 oily solid, which contained no active oxygen. The yellow oily solid (5.1 parts) was extracted with sodium bisulfite solution and yielded 2.1 parts of insoluble material consisting essentially of phenanthrene (an ozone attack of 55% based on the phenanthrene charged). The sodium bisulfite soluble material amounted to 2.9 parts (51% yield based on the phenanthrene charged), and was shown to be essentially diphenaldehyde by infrared analysis.

50 The considerable reduction in the yield obtained indicated that an excess of water (viz: 50% by weight) cannot be present during the ozonation step.

We claim:

1. In a method of making diphenaldehyde wherein ozone is contacted with phenanthrene in the presence of methyl alcohol to form an ozonation product, the improvement comprising heating the ozonation product in the presence of water at a pH below 7.5 to effect hydrolytic decomposition of said product to form diphenaldehyde and hydrogen peroxide, distilling off said alcohol in substantially anhydrous form, and separating diphenaldehyde from the reaction mixture.

2. In a method of making diphenaldehyde wherein ozone is contacted with phenanthrene in the presence of methyl alcohol to form an ozonation product, the improvement comprising contacting phenanthrene, suspended in a medium consisting essentially of methyl alcohol containing up to 35% by weight water, with about one mole of ozone to form an ozonation product, heating the reaction mixture to its boiling point at a pH below 7.5 to effect hydrolytic decomposition of said ozonation product to form diphenaldehyde and hydrogen per-

oxide, concomitantly distilling off said alcohol in substantially anhydrous form, and separating diphenaldehyde from the hydrogen peroxide by solvent extraction.

3. In a method of making diphenaldehyde wherein ozone is contacted with phenanthrene suspended in methyl alcohol to form an ozonation product, the improvement comprising adding water to the reaction mixture containing the ozonation product, heating the resulting mixture at a pH below 7.5 to effect hydrolytic decomposition of

said ozonation product to form diphenaldehyde and hydrogen peroxide, distilling off said alcohol in substantially anhydrous form, and separating diphenaldehyde from the hydrogen peroxide.
